ATTORNEYS

UNITED STATES PATENT OFFICE.

WILLIAM BELSKY, OF NEW YORK, N. Y., ASSIGNOR TO PARAGON BUTTON CORPORATION, OF NEW YORK, N. Y., A CORPORATION OF NEW YORK.

BUTTON.

Application filed April 25, 1924. Serial No. 709,019.

To all whom it may concern:

Be it known that I, WILLIAM BELSKY, a citizen of the United States, and a resident of the city of New York, borough of 5 Queens, in the county of Queens and State of New York, have invented a new and Improved Button, of which the following is a full, clear, and exact description.

The present invention relates to new and 10 useful improvements in buttons, and it pertains more particularly to buttons especially adapted for use in connection with the button-sewing machine foot described in a co-pending application filed by me November 12, 1923, Serial No. 674,331.

It is one of the objects of the present invention to provide a button which may be readily placed in position in the foot of a button-sewing machine in order to insure 20 proper alinement and positioning of the stitch-receiving openings of the button with the needle of the machine.

It is a further object of the invention to construct the button in such a manner that 25 the same will be retained in this position against accidental displacement during the sewing operation.

With the above and other objects in view, 30 reference is had to the accompanying drawings, in which—

Figure 1 is a perspective view of a button constructed in accordance with the present invention;

Fig. 2 is a transverse sectional view thereof, taken on the line 2—2 of Fig. 4;

Fig. 3 is a transverse sectional view thereof, taken at right angles to Fig. 2 and on the line 2—2 of Fig. 4;

Fig. 4 is a top plan view of the button; Fig. 5 is a perspective view of a slightly 40 modified form of button;

Fig. 6 is a transverse sectional view thereof.

Referring more particularly to the drawings, the button comprises a body portion 45 10, which although shown as circular in form, may be of other shapes if desired. The button body is provided with a relatively deep channel 11 extending transversely of the body portion, and such channel is preferably rectangular in form. The reference numeral 12 designates the thread openings of the button, and said thread openings pass through the button from the bottom wall of the channel to the bottom of 55 the button, as shown in Figs. 2 and 3.

In that form of the invention shown in Figs. 5 and 6, a channel 15 is formed on the bottom face of the button, the thread openings 16 extending through the top face 60 thereof. This particular form of the invention permits of ornamentation of the top face of the button without disfiguration of said ornamentation by the transversely extending channel. 65

What is claimed is:

A button having a plurality of thread openings therein and a channel passing across one of the faces of the button and intersecting said thread openings whereby 70 the button is adapted to be retained in position in a button-sewing-machine with its thread openings beneath the needles of the machine by engagement of a part of the machine with said channel.

WILLIAM BELSKY.
